UNITED STATES PATENT OFFICE.

LOUIS M. SINGER, OF TORONTO, ONTARIO, CANADA.

BUMPER.

1,419,318.

Specification of Letters Patent. Patented June 13, 1922.

Application filed October 31, 1921. Serial No. 511,622.

To all whom it may concern:

Be it known that I, LOUIS M. SINGER, a subject of the King of Great Britain, and resident of 154 Simcoe St., in the city of 5 Toronto, county of York, Province of Ontario, in the Dominion of Canada, have invented certain new and useful Improvements in Bumpers, of which the following is a specification.

10 The invention relates to improvements in vehicle bumpers as described in the present specifications and shown in the accompanying drawings that form a part of the same.

The invention consists essentially of the 15 novel features of construction whereby impact receiving members adapted for independent use or in conjunction with the horizontal bumper are vertically arranged in relation to the vehicle.

20 The objects of the invention are to provide one or more members capable of resisting impact delivered above or below the position occupied by the ordinary bumper, to provide a backing for the horizontal bumper, to 25 and generally to provide a bumper which will be inexpensive of construction, simple of adjustment, efficient in operation and durable.

In the drawings Figure 1 is a perspective 30 view showing a bumper bracket secured to the forward end of the vehicle frame and carrying horizontal and vertical impact receiving members, a portion of the horizontal member being broken away.

35 Figure 2 is a perspective view showing a vertical impact receiving member secured to the bracket.

Figure 3 is a perspective view of the vertical impact receiving member.

40 Figure 4 is a perspective view showing a bracket carrying a horizontal impact receiving member and a vertical impact receiving member of modified construction.

Figure 5 is a perspective view showing the 45 form of vertical impact receiving member shown in Figure 4 secured to the bracket.

Figure 6 is a perspective view of the impact receiving member shown in Figure 5.

Figure 7 is a perspective view of the 50 bracket.

Like numerals of reference indicate corresponding parts in the various figures.

Referring to the drawings 1 are the supporting brackets, of which there are preferably two, each consisting of a metal strap shaped to follow the contour of the frame 2

and having its lower end 3 curved to receive the substantially pointed front end of said frame and being adapted to be secured to said frame in any desired manner, said strap 60 being provided with a forwardly projecting horizontal head 4 presenting an enlarged flat face 5 pierced to provide bolt openings 6 located above and below said head and having outwardly projecting side flanges 7 65 and 8, the flange 7 located on the outer side of the bracket preferably being equal in length to the thickness of a bumper bar while the flange 8 is of considerably greater length. 9 are impact receiving members, 70 each comprising a flat outer portion having its ends turned backwardly in special relation to said flat portion and provided with bolt openings 10 adapted to register with the openings 6 in the faces of the brackets 75 for the reception of the threaded ends 11 of substantially U shaped bolts 12 employed to rigidly secure said impact receiving members to the respective brackets.

Where it is desirable to use both the vertical and horizontal forms of impact receiving members the backwardly turned ends 13 of said horizontal members are inserted between the bolts 12 and the pierced ends of said vertical members, the flanges 8 forming 85 stops to prevent longitudinal movement of said horizontal member.

It will thus be apparent that as the impact receiving portion of the horizontal bar is positioned in advance of the impact receiving portion of the vertical member said vertical member constitutes a resilient backing for said horizontal member as well as constituting a means for receiving impact delivered above or below said horizontal member.

In Figures 4, 5 and 6 a modified form of vertical impact receiving member is shown, said member being in the form of a straight bar 14 provided with bolt openings 15 adapted to register with the openings 6 in the faces of the supporting brackets and to be secured in position by means of the U bolts 12. The ends of the bars 14 may be rounded as indicated by the numeral 16 or may be 105 square, as desired.

Where the horizontal bar is to be incorporated with the vertical bar, the ends 18 of said horizontal bar are simply inserted between the bolts 12 and the vertical bar and 110 said bolts tightened by means of the nuts 17.

If desirable where the vertical bars 14 are

to be used alone they may be secured to the brackets by means of bolts 18 in place of the U bolts 12 or other suitable form of fastening means may be employed.

5. In the operation of the invention when both horizontal and vertical bars are employed the vertical bars take care of the impact delivered above or below the horizontal bars and also form a backing for the horizontal bar in cases where the blow received by said horizontal bar is very severe.

What I claim is:—

1. In a vehicle bumper, the combination with the projecting channel portions of the vehicle frame, of bumper supports each comprising a base adapted to be secured in rigid engagement with the top side of a channel portion and having a hook end projecting around the outer ends of said projection, and forward extensions terminating in vertical flat faces provided with bolt openings therethrough, and vertical impact receiving members adapted to be secured in engagement with said faces.
2. In a vehicle bumper, the combination with the projecting channel portions of the vehicle frame, of bumper supports having base portions fitting around the forward ends respectively of said projections and having forward extensions terminating in flat vertical faces, said faces being provided with forwardly projecting side flanges, vertical impact receiving members abutting said faces respectively, a horizontal impact receiving member having backwardly folded ends engaging said vertical impact re-

ceiving members and fastening members extending through openings in said vertical impact receiving member and said faces and locking said horizontal impact receiving member to its position.

3. In a vehicle bumper, in combination, bumper supports having forward projections terminating in flat vertical faces, bumpers comprising vertically arranged bars having backwardly turned meeting ends abutting said faces respectively, a horizontal impact receiving member having backwardly folded ends engaging the backwardly turned ends of said vertical impact receiving members, and fastening members extending through openings in the ends of said vertical impact receiving members and said faces and locking said horizontal impact receiving member to its position.

4. In a vehicle bumper, in combination, bumper supports, a horizontal impact receiving member having backwardly turned ends secured to said supports, auxiliary bumpers comprising vertically arranged bars positioned to the rear of said horizontal impact receiving member and free of engagement therewith and having backwardly turned ends engaging the ends of said horizontal bar, and means for securing the ends of said bars to said supports.

Signed at the city of Toronto, this 21st day of October 1921.

LOUIS M. SINGER.
